UNITED STATES PATENT OFFICE.

CLARENCE A. HOLDREDGE, OF CHICAGO HEIGHTS, ILLINOIS, ASSIGNOR TO
DAVID S. WEGG, OF CHICAGO, ILLINOIS.

BONDING-PIN AND METHOD OF MAKING SAME.

SPECIFICATION forming part of Letters Patent No. 691,313, dated January 14, 1902.

Application filed November 18, 1901. Serial No. 82,778. (No model.)

To all whom it may concern:

Be it known that I, CLARENCE A. HOLDREDGE, a citizen of the United States, residing at Chicago Heights, county of Cook, State of Illinois, have invented a certain new and useful Improvement in Bonding-Pins and Methods of Making the Same; and I declare the following to be a full, clear, and exact description of the invention, such as will enable others skilled in the art to which it pertains to make and use the same, reference being had to the accompanying drawings, which form a part of this specification.

My invention relates in general to improvements in electric connectors for uniting a wire or other small electric conductor to a larger conductor, and more particularly to a bonding-pin for securing a wire within holes formed in the adjoining rails of a railroad-track.

In bonding rails it is necessary that the terminals of the bond should be closely and securely connected to the rails throughout a sufficient portion of their surfaces to insure the electrical contact requisite for the passage of the current.

An object of my invention is to provide a bonding-pin capable of being readily placed upon an end of the bond and of being then driven into an opening through the rail, thereby securely fastening the bond to the rail and forming an electrical connection between the bond and rail of the necessary capacity.

A further object of my invention is to provide a bonding-pin which will be inexpensive in manufacture, simple in application, and efficient in use.

My invention consists, essentially, in a bonding-pin composed of grooved portions united at their ends by integral straps.

My invention further consists in a bonding-pin comprising two grooved semicircular tapered portions connected at their smaller ends by integral straps.

My invention still further consists in a method for making a bonding-pin.

My invention will be more fully described hereinafter with reference to the accompanying drawings, in which the same is illustrated

as embodied in a convenient and practical form, and in which—

Figure 1 is a longitudinal section through a bonded rail-joint, showing the application thereto of my improved bonding-pin; Fig. 2, 55 an edge view of a blank from which my bonding-pin is formed; Fig. 3, a plan view of the blank illustrated in Fig. 2; Fig. 4, a perspective view of the completed bonding-pin, and Fig. 5 a transverse sectional view on line 55 60 of Fig. 4.

The same reference characters are used to indicate the same parts in the several figures of the drawings.

Reference-letters A and A' indicate the adjoining ends of two rails, while reference-letters B and B' indicate the usual joint-plates secured to the opposite sides of the rail-joint by any suitable means—such, for instance, as bolts and nuts on the ends thereof. Openings a and a' are provided in the adjoining rails, such openings being preferably formed through the webs of the rails.

C indicates a bond, which may consist of a wire conductor the opposite ends of which 75 are secured within the openings a and a' of the adjoining rails to electrically unite the same. In order that the wire conductor may be closely and securely connected to the rails, it is necessary that a bonding-plug or channel-pin should be interposed between the ends of the wire conductor and the walls surrounding the holes through the rails.

D indicates my improved bonding-pin, which consists in a plurality (preferably two) 85 of longitudinal grooved portions united so as to form a hollow pin. The grooved portions are preferably tapered and are united at their smaller ends by straps d' d', preferably formed integral with the grooved portions of the pin. While the bonding-pin 90 may be constructed in any suitable manner, it has been found in practice that it may be advantageously constructed as follows: A blank is rolled into the shape illustrated in 95 Figs 2 and 3, such blank being tapered both on its flat surfaces and edges from its outer ends toward the center thereof, as clearly indicated in the figures referred to. An opening d is then punched through the reduced 100

central portion of the blank, thereby forming straps $d' d'$ on either side of such opening. The blank then consists in two tapered portions united at their smaller ends by integral straps $d' d'$. The blank is then stamped so as to assume a semicircular shape with a longitudinal central groove. The blank is then bent upon the connecting-straps $d' d'$, so that the two end portions are brought together, forming a hollow pin, such as illustrated in Fig. 4.

The bonding-pin may be conveniently applied in the following manner: The end of the smaller conductor, which is usually a wire, is passed through the opening a in the rail and the bonding-pin then placed around the end of the wire, as shown at the left of Fig. 1, with the reduced or smaller end thereof adjacent to the opening through the rail. The smaller end of the pin when around the wire being slightly smaller than the diameter of the opening through the rail the pin may be readily driven into the opening by applying power to the larger end thereof. The taper of the pin, while permitting the latter to be easily driven into the hole through the rail, does not prevent an extended and close contact between the pin and the wall surrounding the hole, as clearly indicated at the right of Fig. 1.

From the foregoing description it is evident that I have devised a simple and efficient bonding-pin comprising two portions bent together, thereby forming a hollow pin of a diameter substantially the same as that of the smaller conductor or bond. It is also evident that I have devised a simple and convenient method of constructing such bonding-pin, such method, generally stated, consisting in forming the pin in two alined portions connected by integral straps and then bending the portions together to form a hollow pin.

While I have described more or less precisely the details of construction, I do not wish to be understood as limiting myself thereto, as I contemplate changes in form, the proportion of parts, and the substitution of equivalents, as circumstances may suggest

or render expedient, without departing from 50 the spirit of my invention.

Having now fully described my invention, what I claim as new, and desire to secure by Letters Patent, is—

1. A bonding-pin composed of a plurality of grooved tapered portions united by straps, substantially as described. 55

2. A bonding-pin composed of a plurality of tapered grooved portions connected at their smaller ends by integral straps, substantially 60 as described.

3. A bonding-pin composed of semicircular grooved tapered portions united at either side of their smaller ends by integral straps, substantially as described. 65

4. In a bonding-pin, the combination with two grooved tapered portions, of integral straps the ends of each of which are united to the smaller ends of the tapered portions of the pin, substantially as described. 70

5. The method of making a bonding-pin which consists in forming the same in two grooved alined portions, and then bending the portions together to form a hollow pin, substantially as described. 75

6. The method of constructing a bonding-pin which consists in rolling a blank, punching an opening through the central portion, forming a central longitudinal groove therein, and bending the portions of the blank together to form a hollow pin, substantially as 80 described.

7. The method of making a bonding-pin which consists in rolling a tapered blank larger at each end than at the center, punching an opening through the reduced central portion, stamping the blank into semicircular portions having longitudinal grooves therein, and bending the semicircular portions together to form a hollow pin, substantially as 85 described. 90

In testimony whereof I sign this specification in the presence of two witnesses.

CLARENCE A. HOLDRIDGE.
